H. S. FOLKER.
DIAPHRAGM VALVE.
APPLICATION FILED AUG. 4, 1915.

1,284,287

Patented Nov. 12, 1918.

WITNESSES:

S. W. Johnson

INVENTOR.

BY

ATTORNEY.

UNITED STATES PATENT OFFICE.

HOWARD S. FOLKEE, OF OROVILLE, CALIFORNIA, ASSIGNEE TO THE NATIONAL SAFETY APPLIANCE COMPANY, OF SAN FRANCISCO, CALIFORNIA, A CORPORATION OF CALIFORNIA.

DIAPHRAGM-VALVE.

1,284,287.

Specification of Letters Patent. Patented Nov. 12, 1918.

Application filed August 4, 1915. Serial No. 48,502.

To all whom it may concern:

Be it known that I, HOWARD S. FOLKEE, a citizen of the United States, and a resident of the city of Oroville, county of Butte, 5 and State of California, have invented certain new and useful Improvements in Diaphragm-Valves, of which the following is a specification.

The invention relates to valves automatically operated by differences in fluid pressure, designed particularly to be used in the operation of automatic train stopping mechanism. The structure is so designed that the venting of a portion of the fluid pressure 15 of a particular chamber in the valve mechanism will cause the train stop to operate, giving a service application of brakes.

One of the objects of the invention is to provide a double diaphragm valve, the effective area of one of the diaphragms being greater than the other.

Another object is to so construct a double diaphragm valve that a leak will cause the valve to operate to perform its necessary function in the same manner as though the operative fluid were purposely vented.

Another object is to provide a valve construction which will cause the valve to be opened by venting a fluid pressure and to be closed by applying a fluid pressure.

Another object of the invention is to provide a valve which is simple in its construction, yet certain and sensitive in its operation, and will give a warning signal should a leak occur.

Other objects will appear from the following description and claims.

Referring to the drawings forming a part of this specification:

Figure 1 is a central longitudinal section of the improved valve and valve chamber, with the connections for applying and venting the fluid pressure and also a fragmentary portion of the chamber in which the operative fluid performs its ultimate function.

Fig. 2 is a detail showing the diaphragms in side elevation, the central ring between the diaphragms being shown in section.

In the drawings similar reference characters indicate like parts.

The valve casing B is provided with a cylindrical portion b inclosing the chamber d. The diaphragms h and i are spaced 55 apart by rings u and v at the periphery

and center respectively and they are clamped in place at their periphery between a seat w' and an annular flange b' on the cover plate B', the said cover plate B' being secured to the cylinder A by means of bolts A' to in any suitable way. The ring u held at the outer edges of the diaphragm, is provided with an annular groove w in its periphery and with an annular groove w' in one of its sides and is also provided with a plurality of radial vents u' as shown, and the said ring is so constructed with respect to the seat w' and the flange b' that the exposed surface area of the diaphragm h is greater than that of the diaphragm i.

The construction of the valve and its connections with the diaphragm will now be described.

The valve consists of a rod j having an elongated screw-threaded shank j'. Extending centrally of the stem is a restricted passage e which is opened to the chamber d by a port e'. A fitting r passes through central openings in the diaphragms h and i and it is securely fastened to the same by a nut r' which holds in place the inner ring v and the central portions of the diaphragms. The fitting r is provided with a central screw-threaded opening into which the valve stem j' extends, and the said stem is held in place by a lock nut r'' as shown.

The head of the valve j which is carried by the fitting r is constructed to co-act with the valve seat k in the hollow fitting K secured to the central portion of the cylinder head. A nozzle F provided with a restricted passage f is held to the fitting r in a position opposite to the valve j, and the restricted passage f in the nozzle F is in line with the restricted passage e in the valve stem j'. Another fitting Q provided with a screw-threaded shank q is secured to the cover plate B'. This fitting is provided with a valve seat q', a passage q'', a chamber q''' and a vent q''. A valve O provided with a head o is normally held in closed position on the valve seat q' by a spring w, one end of which contacts with a shoulder on the head of the valve O, the other end impinging on a shoulder w' of the plug W secured to the fitting Q.

From the above description, it will be seen that there are formed two chambers d and g in the valve casing on opposite sides of the double diaphragms and also what may

be termed a neutral chamber *s* between the two diaphragms. The radial vents *u*⁴ in the ring *u* are in line and co-act with radial vents *t* in the walls of the casing *B*, so that 5 the chamber *s* is at all times open to the atmosphere.

a is a supply passage in the structure supporting the valve casing and it is connected with the chamber *d* by a supply port *c* by 10 means of which fluid pressure may be supplied through the passage *a* into the chamber *d*. The passage way *a* is controlled by a supply valve not shown.

A pipe *n* leads into the chamber *g* through 15 a passage way *m'*—*m* in the head *B'* of the valve casing and the said pipe *n* is connected to a suitable venting valve not shown.

The operation of the structure will now be described.

20 The valve *j* is assumed to be in its closed position as shown in Fig. 1. When the controlling valve of the passage *a* is opened, fluid flows through the passage way *a* and port *c* thereby exerting pressure in the chamber *d*. The fluid enters the restricted passage port *e'* through the restricted passage ways *e* and *f* into the chamber *g*, which being closed, will cause pressure to be exerted upon the face of the larger diaphragm *h* 25 thereby holding the valve head *j* securely seated against the seat *k*. When the venting valve connected to the passage *n* is operated, the pressure is diminished in the chamber *g* to such a degree that the differential of pressure on the diaphragm is such 30 that the valve structure will be forced in the direction of the arrow *X* in Fig. 1 causing the restricted passage-ways *e* and *f* to be closed by the head *o* of the valve *O*, thus 35 causing the entire supply of fluid passing through the conduit *a* to enter the chamber *l* to operate the mechanism contained therein. Further fluid pressure causes the nozzle *F* to impinge against the valve *O* and 40 to thus unseat the said valve thereby lowering the pressure in chamber *g* to the normal pressure of the atmosphere.

In the event that there should be a leak 45 through the diaphragm *h*, then it is seen that the air in the chamber *g* will vent itself through the chamber *s* and ports *u*⁴ and *t*, so that the diaphragms will then operate in the same manner as though the chamber *g* was purposely vented to the atmosphere as 55 above described.

This is evident for the reason that any 60 leakage of the larger diaphragm *h* either around its circumference or at the center or by fracture, will cause a flow of fluid into the chamber *s* thence through ports *t* and *u*⁴ to the atmosphere. When this leakage is greater than the supply through the restricted port *f*, the pressure from the chamber *g* will be reduced and will cause 65 the valve to open as hereinbefore described.

Furthermore, leakage past the diaphragm *i* at any point will cause a flow of fluid into the chamber *s* and thence to the atmosphere through the ports *t* and *u*⁴ causing a whistling noise to be made thereby giving warning.

From the above description, it will be seen that the chamber of the train stop which is vented is supplied with fluid pressure through a restricted air passage of fixed 75 capacity and much smaller than the valve which vents the chamber, so when the valve which vents the chamber is opened, the pressure in the chamber is reduced very rapidly.

When all parts are in their normal position, the venting valve is closed. If this valve should leak more than the capacity of the restricted passage which supplies the chamber, it will reduce the pressure in said chamber thereby causing the train stop to 80 operate. This action will also take place if any of the pipes or fittings leading to this chamber should leak or be disconnected or damaged.

While the above described construction 85 forms a positive and efficient instrument, it is to be understood that details of construction may be changed without departing from the spirit and scope of my invention.

I desire it also to be understood that the 90 language used in the following claims is intended to cover all of the generic and specific features of the invention herein described, and all statements of the scope of the invention which, as a matter of language, might be said to fall therebetween.

Having now described my invention, what I claim as new and desire to secure by Letters Patent, is:

1. In a valve mechanism, a valve chamber, a venting chamber, double diaphragms between the two chambers, an inlet passage to the first mentioned chamber and an outlet passage to the second mentioned chamber, said outlet passage controlled by a 100 normally seated spring pressed valve, means supported by the diaphragm for opening said valve.

2. In a valve mechanism, a double diaphragm, a valve rigidly secured to and movable with both members of said double diaphragm, chambers on either side of the double diaphragm, said valve being provided with a restricted passage way, to permit pressure to be exerted on the double 115 diaphragm to normally keep said valve seated.

3. In a valve mechanism, a double diaphragm supporting a valve structure, chambers on either side of the double diaphragm, 125 said valve being provided with a restricted passage-way connecting the two chambers, means for closing said restricted passage-way when the valve is open.

4. In a valve mechanism, a double dia-

phragm, a main valve attached thereto, a venting valve, means for causing a differential of pressure on the said diaphragm to hold the valve normally closed when the 5 venting valve is seated and means for seating said venting valve.

5. In a valve mechanism, a double diaphragm, a valve rigidly attached thereto and positively movable with both members 10 of said double diaphragm, and means for opening the valve by venting the fluid pressure.

6. In a valve mechanism, a double dia-

phragm, a main valve attached thereto a venting valve, means for causing a difference of pressure on said diaphragms to open each of said valves. 15

In witness whereof I have hereunto set my hand at the city of Oroville, county of Butte, and State of California, this 9th day 20 of July, 1915.

HOWARD S. FOLKER.

In presence of—

HARRY L. RODERICK,
HOMER C. DOUGLAS.
